UNITED STATES PATENT OFFICE.

CHARLES H. MORGAN AND ALBERT J. GIFFORD, OF WORCESTER, MASSACHUSETTS; SAID GIFFORD ASSIGNOR TO SAID MORGAN.

GAS-PRODUCER.

No. 852,516.

Specification of Letters Patent.

Patented May 7, 1907.

Application filed June 3, 1904. Serial No. 210,938.

To all whom it may concern:

Be it known that we, CHARLES H. MORGAN and ALBERT J. GIFFORD, both citizens of the United States, residing at Worcester, in the county of Worcester and Commonwealth of Massachusetts, have invented a new and useful Improvement in Gas-Producers, of which the following is a specification, accompanied by drawings forming a part of the same, in which—

Figure 1 represents a vertical central sectional view of a gas producer embodying our invention, the section being shown on line 1—1, Fig. 2. Fig. 2 is a plan view of our improved gas producer, and Fig. 3 is a sectional view of one half of the producer on line 3—3; Fig. 1, and Fig. 4 is a vertical sectional view of a portion of the side wall of the gas producer taken on the plane of one of the gas outlets 25.

Similar reference letters and figures refer to similar parts in the different views.

Our improved gas producer belongs to that class of producers known as suction or down draft producers in which the supply of air for supporting combustion is received at the top of the gas producer chamber and is conducted downward through the fuel, and our invention consists in certain features of construction and novel arrangement of parts as hereinafter described and set forth in the annexed claims.

Referring to the accompanying drawings 1 denotes the heating chamber inclosed by a side wall 2 preferably circular and constructed of masonry. The chamber 1 is covered by a circular plate 3 provided at the center with a downwardly projecting tube 4, forming a twyer, through which air is admitted 40 to the heating chamber. At the lower end of the tube 4 I support a nozzle 5 extending some distance below the lower end of the pipe 4 and preferably covered on its exposed outer surface by a covering of asbestos 6 to protect 45 it against heat. The nozzle 5 is readily removable from the tube 4 through the upper end of the tube to enable it to be replaced when injured by the excessive heat of the gas producer, and in the present instance it is supported by a flange 7 on the upper end of the nozzle 5 which rests upon interior shoulder 8 in the tube 4. The top plate 3 is also provided with openings 9 closed by covers 10 to provide for the admission of fuel and also to

permit the fuel to be properly distributed by 55 pokers or otherwise within the heating chamber 1.

The cover 3 is provided with an annular concentric flange 11 extending upward from the cover 3 upon which is supported a supplemental or top cover 12 provided with a concentric opening 13 directly over the tube 4 and closed by a removable cover 14. Inclosing the side wall 2 is a metal shell 15 and concentric with the shell 15 is a similar metal 65 shell 16 having its lower end connected with the shell 15 and its upper end riveted to the annular flange 11. Between the shells 15 and 16 is an inclosed annular space 17 which is closed at the bottom and communicates at 70 the top with the air space 18 between the cover 3 and the supplemental or top cover 12. Outside the metal shell 16 is a masonry wall 19 inclosing an annular space 20 and protected against the radiation of heat by an 75 outer sand wall 21 retained by a concentric metal shell 22. The several covering plates 3, 10, 12 and 14 are provided with depending flanges which are embedded in sand in order to sand-seal said covers. The side 80 walls of masonry 2 and 19 are supported upon a concentric base wall 23 provided with interior recesses 24 which communicate with the lower end of the annular space 20.

On diametrically opposite sides of the gas 85 producer are outlet gas pipes 25 communicating with the annular space 20 through which gas, as it is produced in the chamber 1, is withdrawn, the movement of the gas being indicated by the arrows 26, 26, Figs. 1 and 4, 90 the withdrawal of the gas being effected by suction, either by means of the reciprocating piston of a gas engine, a suction fan, or other suitable mechanical device. Communicating with the annular space 17 near its lower 95 end, are pipes 27 opening to the outside air, whereby a current of air is supplied in the direction of the arrows 29 through the annular space 17, air space 18 and downward through the nozzle 5 into the body of the coal contained in the gas producer chamber 1. Water pipes 30 are inserted in the upper end of the annular space 17 and are connected with a source of water supply, with their free ends provided with spraying nozzles 31 by which 105 a spray of water is made to impinge against the opposing walls of the space 17 down which the water trickles and is collected at

the bottom of the annular space 17, as shown at 32, the water accumulating until it reaches the open pipes 27 which then serve as overflow pipes. As the space 17 is situated next to the inner wall 2 of the gas producer, it receives more or less radiant heat from the combustion of coal in the gas producer chamber 1, and the metal shelf 16 by which the space 17 is separated from the annular space 20 also becomes heated by the upward flow of heated gas through the space 20 to the outlet pipes 25. The heat which is thus imparted to the annular space 17 vaporizes a considerable portion of the water supplied by the spraying nozzles 31 and the steam thus formed becoming intimately mixed with the ascending current of air is fed through the nozzle 5 downward into the body of incandescent coal in the chamber 1. The masonry walls surrounding the gas producing chamber are supported upon metallic legs 33 which rest upon the bottom of a pit 34, which is partially filled with water during the operation of the producer, and from which ashes as they are formed are raked from the producer. The inner wall 2 of the gas producer is contracted near the top of the chamber 1 to form a restricted throat opposite the nozzle 5, whose least diameter is at a point 35 a short distance above the lower end of the nozzle 5. Below the nozzle 5 the diameter of the gas producing chamber gradually expands to its normal diameter. By this shape of the inner walls of the producing chamber, the upper end of the chamber becomes slightly hopper shaped to facilitate the feeding and massing of the fuel compactly around the nozzle 5, while the enlargement immediately below the nozzle provides for a freer passage and distribution of air through the center of the mass of fuel and tends to prevent adherence of clinkers to the walls of the producer.

We are aware that suction or down draft gas producers are not new and we are also aware that it is not new to heat the air supply by which combustion is maintained in producers of this class, but so far as we are aware the heating of the air supply has been accomplished by carrying the air supply pipe through an auxiliary chamber outside of and entirely independent of the gas producer chamber, said auxiliary chamber being heated by the current of heated gas as it was withdrawn from the gas producer chamber.

By our improved construction we conduct the air supply to the gas producer chamber through the annular space 17 concentric with the gas producer chamber 1, thereby utilizing the radiant heat from the gas producer chamber and we surround the air space 17 with a similar concentric gas space 20, thereby largely increasing the heating surface, due to the increase in the diameter of the separating shell 16 and as several water pipes 30 are

conducted to the space 17 on different sides of the gas producer, four being employed in the present instance, the ascending current of air through the space 17 becomes thoroughly impregnated with steam. The upwardly moving steam charged current of air through the space 17 also tends to prevent the over-heating of the side walls of the chamber, thereby obviating the sticking of clinkers to the wall while the body of water collected at 32 in contact with the lower end of the wall 2 tends to reduce the temperature at the bottom of the gas producer chamber, so that the clinkers passing downward with the body of ashes remain separated and can readily be withdrawn from the water sealed pit 34.

What we claim as our invention and desire to secure by Letters Patent is:—

1. In a gas producer, the combination with a gas producing chamber, of a cover for said chamber, a depending twyer entering the top of said chamber from said cover, an annular air space surrounding said chamber, means for admitting air to the lower end of said air space, means for applying heat to the outer wall of said air space, and means for conducting air from the top of said air space to said twyer.

2. In a gas producer, the combination with a gas producing chamber having a cover, of a twyer depending from said cover and entering said chamber, an annular air space surrounding said chamber, means for admitting air to the lower end of said air space, means for conducting air from the upper end of said air space to said twyer, an annular gas space surrounding said air space and communicating with said gas producing chamber, and an outlet gas pipe communicating with said annular gas space.

3. In a gas producer, the combination with a gas producing chamber, of a twyer at the upper end of said chamber, an annular air space surrounding said chamber, means for admitting air to the lower end of said air space, means for conducting air from said air space to said twyer, and means for spraying water into said air space.

4. In a gas producer, the combination with a gas producing chamber, of an annular air space surrounding said chamber, means for admitting air to the lower end of said air space, means for conducting air from the upper end of said air space to the gas producing chamber, said air space having parallel side walls, means for spraying water against said side walls and a water overflow near the lower end of said air space.

5. In a gas producer, the combination with a gas producing chamber, of an annular air space surrounding said chamber and having vertical side walls, means for admitting air to the lower end of said air space, means for conducting air from the upper end of said

air space to the gas producing chamber, means for admitting water to the upper end of said air space and against said side walls, and means for maintaining a body of water at the lower end of said air space.

5 6. In a gas producer, the combination with a gas producing chamber, of an annular air space, surrounding said gas producing chamber, a double cover for said chamber inclosing an air space communicating with said annular air space, and a twyer depending from said double cover through which air from said annular air space is conducted to said gas producing chamber.

15 7. In a gas producer, the combination with a gas producing chamber, of an annular air space inclosing said chamber, an annular gas space inclosing said air space, said air and gas spaces having vertical side walls, a metallic partition between said air and said gas space, means for admitting air to said air space at its lower end, means for conducting air from the upper end of said air space to the gas producing chamber, said annular gas space communicating with said gas producing chamber at the lower end of the chamber, and an outlet pipe for gas leading from said annular gas space.

25 8. In a gas producer, the combination with a gas producing chamber, of a double cover for said chamber inclosing an air space, an

opening for the admission of air from said space into said producing chamber, an air space inclosed in the side wall and communicating with the air space in said cover, and an opening into said wall air space for the admission of air thereto.

35 9. In a gas producer, a gas producing chamber having its side walls vertically parallel at the lower end of said chamber with a contracted section near the upper end of the chamber, by which the diameter of the chamber is reduced, and having its side walls gradually flaring near the upper end of the chamber, a concentric twyer entering the 40 upper end of the chamber, a double cover for said chamber inclosing an air space communicating with said twyer, an annular air space surrounding the vertical wall of the chamber communicating with the space between said covers, and an opening at the bottom of said annular air space for the admission of air.

45 Subscribed at Worcester in the county of Worcester and Commonwealth of Massachusetts this twenty seventh day of May 1904.
